(57) CLAIM

The ornamental design for a sock, as shown and described.

DESCRIPTION

FIG. 1 is a top view of a sock showing our new design; FIG. 2 is a bottom view thereof; FIG. 3 is a top perspective view of the sock in use condition; FIG. 4 is a top view thereof; and, FIG. 5 is a bottom view thereof.

The broken lines showing of a sock is included for the purpose of illustration only and forms no part of the claim design. All surfaces not shown form no part of the claimed design.
